ELIZABETH R. DIENST, OF KANSAS CITY, MISSOURI.

DESIGN FOR A SHOE-LACE FASTENER.

SPECIFICATION forming part of Design No. 33,359, dated October 16, 1900.

Application filed September 13, 1900. Serial No. 29,973. Term of patent 14 years.

To all whom it may concern:

Be it known that I, ELIZABETH R. DIENST, a citizen of the United States of America, residing in Kansas City, in the county of Jackson and State of Missouri, have invented and produced a new and original Design for Shoe-Lace Fasteners, of which the following is a specification, reference being had therein to the accompanying drawings, forming a part thereof.

The leading or material feature of my design consists in the shape of the shoe-lace fastener, as follows: A indicates a flat horizontal portion comprising the base, from one end of which the body is upwardly and rearwardly curved at B, and from the end of this curved portion the body inclines slightly downward in a straight line until near the forward end, which is near the forward end of the portion

A, at which point the body turns in a curve upwardly, as indicated by C. From each side of the base A, near the middle thereof, is a downwardly-extending vertical projection D, which is triangular in shape. From the upper side of the base A, at a point beneath the curve C, rises an arc-shaped projection, the apex of which touches the under side of the curved portion C.

Having described my invention, what I claim as new, and desire to secure by Letters Patent, is—

The design for a shoe-lace fastener as herein shown and described.

In testimony whereof I have signed my name to this specification in the presence of two subscribing witnesses.

ELIZABETH R. DIENST.
